DESIGN FOR A TOASTER CASING

William Miles Cox, Woodside, and Duncan W.
Cox, Hillside Heights, N. Y.

Application February 24, 1947, Serial No. 137,156

Term of patent 14 years

(Cl. D81—10)

To all whom it may concern:

Be it known that we, William Miles Cox and Duncan William Cox, both citizens of the United States, residing in Woodside, Long Island, and Hillside Heights, New York, respectively, have invented a new, original, and ornamental Design for a Toaster Casing, of which the following is a specification, reference being had to the accompanying drawing, forming part thereof.

Fig. 1 is a top plan view of a toaster casing, showing our new design;

Fig. 2 is a front elevational view thereof;

Fig. 3 is a side elevational view thereof; and

Fig. 4 is a fragmentary section generally on line 4—4, Fig. 2.

We claim:

The ornamental design for a toaster casing, substantially as shown.

WILLIAM MILES COX.
DUNCAN WILLIAM COX.
